UNITED STATES PATENT OFFICE.

WILLIAM C. HUEBNER, OF BUFFALO, NEW YORK, ASSIGNOR TO HUEBNER-BLEISTEIN PATENTS COMPANY, OF BUFFALO, NEW YORK.

PHOTOGRAPHIC-PRINTING APPARATUS.

1,377,250.

Specification of Letters Patent. Patented May 10, 1921.

Continuation of application Serial No. 262,076, filed November 11, 1918. This application filed October 1, 1920. Serial No. 414,106.

To all whom it may concern:

Be it known that I, WILLIAM C. HUEBNER, a citizen of the United States, residing at Buffalo, in the county of Erie and State of New York, have invented a new and useful Improvement in Photographic-Printing Apparatus, of which the following is a specification.

This invention relates more particularly to improvements in photographic printing or composing apparatus of the general nature disclosed in various patents granted to me and in my pending applications. These apparatus are intended for photographing any desired number of like or different original prints in any required predetermined and registered position and relative arrangement directly upon the sensitized surfaces of press plates which are afterward suitably finished and used in mechanical printing presses for printing in one or more colors. Such apparatus are adapted for various purposes, such for instance as repeating prints from the same transparent printing plate or negative in a required arrangement on a single sensitized press plate, which, after development, is used for mechanically printing a plurality of impressions; for composing work where it is desired to place different subjects in a predetermined arrangement on the press plate; and for making press plates for multicolor printing where it is necessary to photograph prints in exact register on the different sensitized press plates that are used in presses for printing the different colors.

One object of the invention is to produce an improved photographic printing or composing apparatus of this nature whereby photographic prints can be rapidly made on sensitized press plates in any desired or necessary relative arrangement and position with great accuracy and with the minimum labor, and whereby it is possible to secure results and perform kinds of work, herein-after explained, which are not possible with apparatus heretofore used; other objects of the invention are to produce an apparatus of this nature which is of desirable and practical novel construction; also to design the apparatus so that it is possible with it to secure a direct visual register of the image or images on the printing plate and sensitized plate with those on a layout or

key sheet, previously printed sheet or other representation of a subject with or without register marks; and also to improve and simplify photo-printing or composing apparatus of the kind stated in the respects hereinafter described and set forth in the claims.

In the accompanying drawings:

Figure 1 is a front elevation of a photographic printing or composing apparatus embodying the invention, showing the supports for the sensitized and printing plates swung back away from each other.

Fig. 2 is a sectional plan view thereof on line 2—2, Fig. 1.

Fig. 3 is a similar view thereof showing the parts in position for printing.

Fig. 4 is a front elevation thereof with the parts in the position shown in Fig. 3.

Fig. 5 is an enlarged elevation partly in section of the mechanism for effecting a limited movement of the sensitized and printing plates toward and from each other.

Fig. 6 is a sectional elevation thereof on line 6—6, Fig. 5.

Fig. 7 is an enlarged sectional elevation of the adjusting mechanism for the printing plate holder.

Fig. 8 is an enlarged sectional elevation of the pressure device.

Fig. 9 is an enlarged sectional elevation on line 9—9, Fig. 1.

Fig. 10 is a broken sectional elevation, enlarged, of the device for locking together the main swinging support for the sensitized and printing plates.

Fig. 11 is an elevation of a modification of the master copy holder.

Figs. 12, 13 and 14 are respectively a side elevation, end elevation, partly in section, and plan view, enlarged of one of the registering and scribing devices.

The apparatus hereinafter described in detail comprises essentially a support for a sensitized press plate A; a support for holding a transparent photographic negative or printing plate B (hereinafter called the "printing plate") in front of the sensitized surface of the press plate; a pressure device C or back support for causing an intimate, uniform contact of the sensitized surface with the printing plate; means for causing light to act through the printing plate for photographing the print on the sensitized surface; adjusting means for producing a

relative movement between the sensitized and printing plates parallel with the sensitized surface to enable the prints to be made in predetermined locations and positions on the sensitized surface; and means for producing a relative movement between the sensitized and printing plates toward and from each other to place the plates into contact for printing and to separate them to enable the necessary relative adjustments of the plates. As shown in the drawings the apparatus is constructed as follows:—

20 represents an upright column rising from a supporting base 21 of any suitable 15 sort adapted to stationarily support the column. 22 and 23 represent two swinging supports or frames which are suitably hinged on said column so that they are adapted to swing from the position shown in Fig. 2 in 20 which they extend oppositely from the column to the position shown in Fig. 3, in which they are parallel to each other, for the purpose of placing the printing plate B, which is supported by the frame 23 opposite 25 the sensitized surface of the press plate A, which is supported by the frame 22. As shown, the frame 22 is of substantially U-shape having horizontal upper and lower bars provided at their inner ends with bearing sleeves 22^a surrounding the column 20, and rigidly connected at their outer ends by an upright end bar 22^b, and the frame 23 comprises upper and lower horizontal bars with bearing sleeves 23^a at their inner ends 30 surrounding the column 20 between the bearings for the frame 22, and rigidly connected near their inner ends by an upright bar 23^b. The swinging supports 22 and 23 for the printing plate and the sensitized plate are 35 adapted to be locked together in their parallel position shown in Fig. 3, with the printing plate opposite the sensitized plate by any suitable means, such as vertical bolts 24 at the outer end of the support 23 adapted to 40 enter holes in keepers 25 mounted on the outer end of the other swinging support 22. These bolts 24 are moved into and out of engagement with the keepers 25 by an operating handle 24^a having screw connections 45 with the inner ends of the two bolts, see Fig. 10. The keepers 25 are preferably capable of movement for a limited distance on the swinging support 22 so that when the swinging support 23 for the printing plate 50 holder is bolted to the keepers, it can be moved a slight distance to place the printing plate into contact with the sensitized surface and to remove it to a clearance position a slight distance away from the sensitized surface in order to enable adjustment of the 55 sensitized plate parallel with the surface of this plate to place any desired portion of the sensitized plate in printing position opposite to the printing plate. The means for thus 60 moving the keepers 25 and the support for 65

the printing plate holder is hereinafter explained.

The transparent printing plate B is preferably secured on the glass or transparent supporting plate 26 of a plate holder 27 which is secured on a head 28 which is rotatably mounted in a circular opening in a supporting plate or carriage 29 carried by the main swinging support 23. The plate holder 27 and rotatable head 28 are preferably constructed and mounted on the carriage 29 and adjusted and secured as disclosed in my copending application, Serial Number 248,623, filed August 6, 1918. As fully explained in said application, the printing plate B is adapted to be adjustably secured on the holder 27 and this holder is detachably secured in a predetermined centered position on the rotary head 28 which is adapted to be rotated to and secured in any required adjustment on the carriage 29 by a locking device 30. The head 28 is rotated by a pinion 30^a which is turned by a handle 30^b and meshes with gear teeth on the rotatable head. The plate holder 27 carriage 29 is suitably mounted on the swinging support 23 so that it can be adjusted or moved on the swinging support 23 in a direction perpendicular to the face of the printing plate for the purpose of setting the holder so that different printing plates, regardless of their thickness, can be caused to properly contact with the sensitized surface without deflecting or pressing the sensitized plate out of its intended plane. For instance, the carriage 29 is provided at its upper and lower ends with projecting brackets 31, Fig. 7, adapted to slide in suitable cross guides on the upper and lower arms of the swinging support 23 and the carriage is provided at its four corners with screw-threaded holes in which are adapted to turn adjusting screws 32 which are journaled and held from endwise movement in suitable bearings 33 on the swinging support. These adjusting screws can be rotated simultaneously by any suitable means, such as an upper horizontal shaft 34 connected by spiral gears 35 to the upper screws 32, a similar shaft and spiral gears 36 connecting the two lower screws, and a vertical operating shaft 36 which is turned by a wheel 37 or other means and is connected by a spiral gear 37^a at its upper and lower ends to the upper and lower shafts 34. Any other suitable mechanism for mounting and adjusting the plate holder carriage 29 perpendicularly to the face of the printing plate on the swinging support could be employed.

The sensitized plate A is secured on a holder 38 which is preferably detachably secured on an auxiliary carriage 39 which is adapted to be adjusted vertically on a main carriage 40 which in turn is adapted to be

adjusted horizontally on the swinging support 22. These adjustments of the main and auxiliary carriages are in a plane parallel with the plane of the sensitized surface for the purpose of placing any desired portion of the sensitized plate opposite the printing plate. The sensitized plate holder 38 may be of any suitable construction adapted to have sensitized plates of different sizes secured and stretched thereon so as to hold the plates taut and straight and this holder is preferably detachably secured on the auxiliary carriage so that the plate holder with a sensitized plate secured thereon can be readily secured in place in and removed from the machine. The plate holder shown is constructed and removably mounted on the auxiliary carriage, as fully explained in my said application. 20 41 and 42 represent the clamps or securing means for the upper and lower edges of the sensitized plate, and 43 represents adjusting screws for moving one of the clamps 42 to stretch the sensitized plate on the plate holder.

As shown, the main carriage 40 is arranged to slide between suitable upper and lower guide ways or tracks 44 and 45 on the swinging support 22 and the auxiliary frame 39 is provided with tubular vertical side rods 46 by which it is arranged to slide vertically on the vertical side rods of the main carriage. The main carriage, see Fig. 9, is provided at its lower end with rollers 47 which roll on the lower guide rail 45 and are provided with eccentrically adjustable journals by which the rollers can be adjusted to level up the carriage on the swinging support 22, and the carriage is provided with rollers 48 which roll against the underside of a projecting rail on the swinging support to prevent the carriage from lifting or tilting relatively to the guides. The main carriage can be adjusted horizontally on the swinging support by any suitable means, such for instance as a screw shaft 49 journaled on the swinging frame or support 22 and adapted to turn in a screw-threaded nut secured to or formed on the main carriage. The shaft is adapted to be turned by a handle 50 at its outer end. The auxiliary carriage can be adjusted vertically on the main carriage by any suitable means, such as two screw shafts 51 suitably journaled on the main carriage and having screw threads working in nuts 51^a on the auxiliary carriage. These two screw shafts 51 are rotated simultaneously by an operating shaft 52 suitably journaled on the swinging support 22 and provided at its outer end with a handle 53 for turning it. Spiral gears 54 splined on this shaft mesh with and turn spiral gears fixed on the lower ends of the adjusting screws 51. When the main carriage is adjusted horizontally on

the swinging support the spiral gears 54 slide with the carriage on the operating shaft 52 and always remain in mesh with the gears on the screw shafts, thus enabling the vertical adjustment of the auxiliary carriage in any position of the main carriage.

The sensitized plate holder 38 is not secured directly to the vertically movable auxiliary carriage but is secured on a swinging frame 55 which is hinged at one side of the auxiliary carriage so that this frame can be swung horizontally to place the sensitized plate holder with the sensitized plate A in operative position between the bars of the auxiliary carriage, as shown in Figs. 1 to 3, 75 80 or to permit the frame 55 with the plate holder to be swung back away from this operative position. 56 is a similar swinging frame hinged to the opposite side of the auxiliary carriage 39 to swing from an operative position between the bars of the auxiliary carriage to the position shown in Figs. 1 to 3. This frame 56 is adapted to carry a holder 57 on which is secured a layout or key sheet 58. The holder 57 for this layout or key sheet is like the holder 38 for the sensitized plate and when the swinging frame 56 is swung into operative position within the auxiliary carriage this holder 57 holds the layout or key sheet in the same position 95 that the sensitized plate is held by its holder. The swinging frame 55 for the sensitized plate holder is swung back out of the operative position to permit the frame for the layout or key sheet holder to be swung into 100 the corresponding position. Each of these swinging frames is adapted to be stationarily secured with the holder carried thereby in the operative position within the auxiliary carriage frame by any suitable means, such as upright bolts on the outer end of the swinging frame and adapted to engage keepers in the upper and lower bars of the auxiliary carriage. The bolts shown are like the bolts 24 used for the main swinging 105 support 23. 59, Figs. 1 and 3 indicate the bolts for the swinging frame 56, and 60 their operating handle, and 61 indicates the operating handle for the bolts of the other swinging frame 55. Since both of the 110 frames 55 and 56 are mounted on the auxiliary carriage 39 they partake in the vertical and horizontal adjustments of this carriage. If, therefore, the layout sheet is placed in operative position and adjusted to cause the image on the printing plate to register with an image on the layout sheet, and the layout sheet frame 56 is then swung out of the way and the frame 55 carrying the sensitized plate is swung into its place, the printing plate will register with an exactly corresponding portion of the sensitized plate and a print made on the sensitized plate will occupy exactly the same relation as the image on the layout sheet. Thus, the ar- 115 120 125 130

angement of the images on the layout sheet can be accurately duplicated on the sensitized plate.

The means before mentioned for moving the swinging support 23 to place the printing plate in contact with the sensitized surface and to remove it to the clearance position are preferably constructed as follows:—

The keepers 25 are mounted to slide in suitable guides 66 on the vertical end bar 22^b of the swinging support 22 and are moved by a bar 67 which is arranged to slide in a vertical guide in the bar 22^b and is provided with two inclined or oblique portions each engaging in a correspondingly inclined groove in one of the keepers 25. By moving this bar 67 upwardly the keepers are moved outwardly to move the swinging support 23 away from the support 22 to place the printing plate in the clearance position, and by moving the bar 67 downwardly the keepers and the connected swinging support 23 are moved inwardly to place the printing plate in contact with the sensitized plate. The bar 67 is moved by a lever 68 which is suitably fulcrumed on the outer end of the swinging support 22 and has an arm 69 entering a socket in the bar 67. The printing plate support is moved in the same way to place the printing plate into and out of contact with the layout sheet when the latter has been placed in the operative position opposite the printing plate.

The pressure device C for pressing the sensitized plate into intimate contact with the printing plate is mounted on a swinging frame or support 70 which is suitably hinged at one end to the inner end of the main swinging support 22 so that the frame 70 can be swung to carry the pressure device to and from the operative position back of the sensitized plate shown in Figs. 2 and 3. As shown, the frame 70 is hinged to brackets 71 projecting from the upper and lower bearing sleeves of the support 22. The frame 70 can be secured for holding the pressure device stationary in this position by any suitable means, such as vertical bolts 72, Fig. 1, slidably mounted on the frame 70 and adapted to enter keepers 73 at the top and bottom of the main support 22. The bolts 72 can be similar to the other locking bolts described and similarly operated by a handle 74. When the swinging frame 70 for the pressure device is secured in the position shown in Figs. 2 and 3, the pressure block 75 or head at the inner end of the pressure device can be moved on the frame toward and from the sensitized plate for pressing it against the printing plate and to release the sensitized plate in any suitable manner. As shown, the pressure block 75 is carried by a stem or shaft 76 which is adapted to slide and turn in a suitable bearing 77 on the frame 70 and is moved

by a screw 78 swiveled in the outer end of the shaft 76 and engaging a nut secured to the swinging frame 70. This screw is turned by a wheel 79 at its outer end. The pressure block is preferably mounted on the supporting shaft 76 so that it can be adjusted radially relative to the axis of the shaft 76 and can also be rotatably adjusted either about the axis of the shaft 76 or about an axis eccentric thereto for the purpose of placing the pressure block in any angular position and radial location that may be required by reason of the position of the printing plate with which it is being used. In the construction shown, see Fig. 80 75 80 85 90 95 100 105 110 115 120 125 130

In making prints from the printing plate on the sensitized plate, after adjusting the sensitized plate to the required position for the print and pressing it firmly against the printing plate by the pressure device C, the sensitized plate is exposed to the action of light which passes through the transparent printing plate, the holder for the printing plate, rotary head 28 and carriage 29 on which the holder is mounted, having openings to permit the passage of light. The light can come from any suitable source, such for example as a lamp 87 in the hood or chamber 88 mounted on the back of the plate holder carriage. The hood shown has a hinged back or section adapted to be opened as indicated by broken lines in Figs. 2 and 3 to afford access to the adjusting device for the rotary head 28 and to allow the operator to look through the printing plate for registering the image thereon with the images on the layout sheet. By mounting the layout sheet as explained so that it can be positioned interchangeably with the sensitized plate and placed flat against the outer face of the printing plate on which the image is located, the images on the plate and layout sheet are placed in direct face to face contact and the operator can make a direct visual registration of the images. This insures great accuracy and precludes the possibility of error incident to the use of scales or indicators or calculations which may be erroneous or not exact. The layout sheet can be opaque and can, if desired, be pasted or otherwise mounted on a backing plate and waxed to hold the sheet flat and

straight and prevent atmospheric changes from affecting the sheet, or the layout sheet can, if desired, be transparent, which permits the images thereon to be illuminated 5 by transmitted light of suitable color or character to better aid vision in registering the images. A printed sheet can also be used in the holder 56 in place of a layout sheet when it is desired to make a press plate 10 for printing sheets corresponding precisely with a previously printed sheet.

In some classes of work it is necessary to make printing plates B from the different units or parts of a composite design, such 15 as for example as a label which is produced from several lithographic stones, metal plates, wood cuts or other printing surfaces which may or may not carry suitable register marks, and to repeat the design on a sensitized plate A in accordance with a prescribed layout. In such a case a positive or master impression or copy of the design is made on a glass or other transparent plate or film and this transparent plate, shown 20 at 90 is secured in a suitable holder 91 which is preferably similar to the holder for the printing plate B. This holder is mounted on a skeleton support or frame 92 suitably hinged to the outer end of the swinging 25 printing plate support 23 so that the former can be swung around to place the transparent master plate 90 flat against the face of the printing plate B, as shown in Fig. 1. The printing plate can then be adjusted to 30 secure a direct visual register of the image thereon with the corresponding part of the master design. Prints of this unit are then made from this printing plate on the sensitized plate in accordance with the layout 35 40 on the layout sheet. The printing plates for the other parts of the design are registered and prints made therefrom in a similar manner. Printing plates for the different colors of a color job can be registered in like 45 manner.

After each printing plate has been registered with the master design, register marks 93, Fig. 1, can be scribed on the printing plate by a registering and scribing device 50 94 which comprises a frame hinged on the swinging support 23, preferably at its lower edge, and adapted to be swung up and stationarily secured by catches 95 in front of the printing plate, after the master plate holder has been swung out of the way. The 55 registering device is provided with guide rods or ways 96 arranged at right angles to each other on which are movable slides or carriages 97, see Figs. 12 to 14, each carrying 60 a foot 98 in which is mounted a registering glass 99 provided with fine cross lines. The foot is mounted on a leg 100 which is slidably mounted on the slide and is adapted to be moved toward and from the printing 65 plate by a pinion 101 engaging a rack 102

on the leg to place the registering glass into and out of contact with the face of the printing plate. The slide 97 is adapted to be moved along the guide 96 parallel with the face of the printing plate by a pinion 103 70 engaging a rack 104 on the guide. Preferably the foot 98 is slidably mounted on the leg 100 and is adjusted transversely thereon by a screw 105. 106 represents two scribing blades or points movably or pivotally 75 mounted on the foot 98 at right angles to each other. These blades are normally held out of contact with the printing plate by suitable springs 107 which permit the blades to be moved for marking the printing plate, 80 The registering devices are so located that when the slides are moved on the guides the intersections of the marks on the register glasses and one scribing blade on each foot will follow diametrical lines crossing at the 85 center of the printing plate. 108 indicates a screw in the leg 100 adapted to be engaged with a hole in the foot for locking the latter in position with its register marks on the diametrical line. 90

After a printing plate has been registered with the master design, as above described, register marks can be scribed thereon as indicated in Fig. 1 by the blades 106 and thereafter when it is necessary to use the printing plate for a subsequent job, it can be properly centered and registered in its holder without the use of the master design by causing its register marks to register accurately with the marks on the register glasses of the registering device 94. 95

Fig. 11 shows a master plate holder 91^a which is rotatably mounted in its swinging support 92^a so that it can be angularly adjusted when necessary to correspond with the position of the printing plate. 92^b indicates a screw for securing the holder when adjusted. 105

109 represents a bolt or latch mounted on the base of the machine, and 110 a treadle for moving the bolt to engage and release the swinging support 22 to hold it stationary. In the use of the apparatus the swinging support 22 can be held from movement by this bolt, and the other swinging support 23 moved toward and from the support 22, or both supports can be swung toward and from each other and the support 22 locked stationarily in position by the bolt 109, as desired, depending upon the location 115 of the apparatus in the room or space available for its operation. 120

In the swing type machine described it is possible after one plate has been made by the visual method of registering the negative to the layout sheet, to note the positions of the prints indicated by the dials on the ends of the adjusting shafts 49 and 52 and the succeeding color plates can then be registered by setting them to the positions so 125 130

- indicated. Also a second sensitized plate can be positioned on the holder 56 in place of the layout sheet, and the two plates can be exposed successively after each setting by 5 first swinging one into position and exposing it, and then the other. In this manner two plates can be made with one setting to register, which greatly increases the speed of operation of the machine.
- 10 I claim as my invention:—
1. In a photographic printing apparatus, the combination of a holder carrying a printing plate, two holders carrying respectively a sensitized plate and a layout sheet 15 or the like and movably mounted to interchangeably position either said plate or sheet opposite to and face to face with the printing plate, means for causing a relative movement of said holders toward and from each 20 other to place the printing plate into and out of contact with the opposed plate or sheet, and pressure means for causing an intimate contact of the sensitized and printing plates.
  2. In a photographic printing apparatus, the combination of a holder carrying a printing plate, two oppositely swinging holders arranged to interchangeably position members carried thereby opposite the 25 printing plate, means for causing a relative movement of said holders toward and from each other to place the printing plate into and out of contact with the opposed member, and pressure means for causing an intimate contact of the printing plate and opposed member.
  3. In a photographic printing apparatus, the combination of a holder carrying a printing plate, two holders carrying respectively a sensitized plate and a layout sheet or the like and interchangeably mounted to permit either to move to a position opposite to and face to face with the printing plate, means for moving said printing plate holder to 40 place the printing plate into and out of contact with the opposed plate or sheet, and pressure means for causing an intimate contact of the sensitized and printing plates.
  4. In a photographic printing apparatus, the combination of a holder carrying a printing plate, two holders carrying respectively a sensitized plate and a layout sheet or the like and interchangeably mounted to permit either to move to a position opposite the 45 printing plate, means for causing a relative movement of said holders for placing different portions of said sensitized plate or sheet opposite the printing plate, means for moving said printing plate holder to place the printing plate into and out of contact with the opposed plate or sheet, and pressure means for causing an intimate contact of the sensitized and printing plates.
  5. In a photographic printing apparatus, the combination of a holder carrying a printing plate, two holders carrying respectively a sensitized plate and a layout sheet or the like and interchangeably mounted to permit either to move to a position opposite the printing plate, means for causing a relative movement of said holders toward and from each other to place the printing plate into and out of contact with the opposed plate or sheet, and pressure means for causing an intimate contact of the sensitized and printing plates.
- the combination of a holder carrying a printing plate, two holders carrying respectively a sensitized plate and a layout sheet or the like and interchangeably mounted to permit either to move to a position opposite the printing plate, means for moving said sensitized plate and sheet holders parallel with the sensitized plate for placing different portions of said sensitized plate or sheet opposite the printing plate, means for moving said printing plate holder to place the printing plate into and out of contact with the opposed plate or sheet, and pressure means for causing an intimate contact of the sensitized and printing plates.
6. In a photographic printing apparatus, the combination of a holder carrying a printing plate, two oppositely swinging holders arranged to interchangeably position members carried thereby opposite the printing plate, means for moving said swinging holders parallel with the sensitized plate for placing different portions of the sensitized plate or sheet opposite the printing plate, means for moving said printing plate holder to place the printing plate into and out of contact with the opposed member, and pressure means for causing an intimate contact of the printing plate and opposed member.
7. In a photographic printing apparatus, the combination of a holder carrying a printing plate, two holders carrying respectively a sensitized plate and a layout sheet or the like and interchangeably mounted to permit either to move to a position opposite the printing plate, means for causing a relative movement of said holders toward and from each other to place the printing plate into and out of contact with the opposed plate or sheet, means for causing a relative movement of said holders for placing different portions of said sensitized plate or sheet opposite the printing plate, pressure means for causing an intimate contact of the sensitized and printing plates, and a holder for a transparent master design mounted to move said design to and from a position face to face with the printing plate.
8. In a photographic printing apparatus, the combination of a holder carrying a printing plate, two holders carrying respectively a sensitized plate and a layout sheet or the like and interchangeably mounted to permit either to move to a position opposite the printing plate, means for causing a relative movement of said holders toward and from each other to place the printing plate into and out of contact with the opposed plate or sheet, means for causing a relative movement of said holders for placing different portions of said sensitized plate or sheet opposite the printing plate, pressure means for causing an intimate contact of the sensitized and printing plates.

of the sensitized and printing plates, a holder for a transparent master design mounted to move said design to and from a position face to face with the printing plate, and a scribing and registering device movable to and from an operative position in front of the printing plate.

9. In a photographic printing apparatus, the combination of a holder carrying a printing plate, two oppositely swinging holders arranged to interchangeably position members carried thereby opposite the printing plate, means for causing a relative movement of said holders toward and from each other to place the printing plate into and out of contact with the opposed member, means for causing a relative movement of said holders for placing different portions of said members opposite the printing plate, pressure means for causing an intimate contact of the printing plate and opposed member, and a holder for a transparent master design mounted to move said design to and from a position face to face with the printing plate.

10. In a photographic printing apparatus, the combination of a holder carrying a printing plate, two oppositely swinging holders arranged to interchangeably position members carried thereby opposite the printing plate, means for causing a relative movement of said holders toward and from each other to place the printing plate into and out of contact with the opposed member, means for causing a relative movement of said holders for placing different portions of said members opposite the printing plate, pressure means for causing an intimate contact of the printing plate and opposed member, a holder for a transparent master design mounted to move said design to and from a position face to face with the printing plate, and a scribing and registering device movable to and from an operative position in front of the printing plate.

11. In a photographic printing apparatus, the combination of two supports one of which is mounted to swing to and from a position facing the other, means for securing the swinging support in this position, a printing plate carried by one of said supports, oppositely swinging holders on said other support arranged to interchangeably position members carried by said holders opposite the printing plate, means for adjusting said holders to place different portions of said members opposite the printing plate, means for moving the printing plate into and out of contact with the opposed member, and pressure means for causing an intimate contact of the printing plate and opposed member.

12. In a photographic printing apparatus, the combination of two supports one of

which is mounted to swing to and from a position facing the other, means for securing the swinging support in this position, a printing plate carried by one of said supports, a carriage movably mounted on said other support, means for adjusting said carriage in directions at right angles to each other parallel with the printing plate, oppositely swinging holders on said carriage arranged to interchangeably position members carried by said holders opposite the printing plate, means for moving the printing plate into and out of contact with the opposed member, and pressure means for causing an intimate contact of the printing plate and opposed member.

13. In a photographic printing apparatus, the combination of two swinging supports one of which is mounted to swing to and from a position facing the other, means for securing the swinging support in this position, a printing plate carried by one of said supports, oppositely swinging holders on said other support arranged to interchangeably position members carried by said holders opposite the printing plate, means for adjusting said holders to place different portions of said members opposite the printing plate, means for moving the printing plate into and out of contact with the opposed member, pressure means for causing an intimate contact of the printing plate and opposed member, and a holder for a transparent master design mounted on the support carrying the printing plate to move to and from a position face to face with the printing plate.

14. In a photographic printing apparatus, the combination of two supports one of which is mounted to swing to and from a position facing the other, means for securing the swinging support in this position, a printing plate carried by one of said supports, oppositely swinging holders on said other support arranged to interchangeably position members carried by said holders opposite the printing plate, means for adjusting said holders to place different portions of said members opposite the printing plate, means for moving the printing plate into and out of contact with the opposed member, pressure means for causing an intimate contact of the printing plate and opposed member, and a holder for a transparent master design, and a scribing and registering device each mounted on the support carrying the printing plate to move to and from a position facing the printing plate.

15. In a photographic printing apparatus, the combination of two supports one of which is mounted to swing to and from a position facing the other, a printing plate mounted on the swinging support, swinging holders on said other support arranged to

- interchangeably position members carried by said holders opposite the printing plate, means for securing said supports together facing each other and moving the swinging support a limited distance toward and from the other support for placing the printing plate into and out of contact with the opposed member, means for adjusting said holders to place different portions of said members opposite the printing plate, and pressure means for causing an intimate contact of the printing plate and opposed member.
16. In a photographic printing apparatus, the combination of a holder carrying a printing plate, two holders carrying respectively a sensitized plate and a layout sheet or the like and arranged to interchangeably position said sensitized plate and layout sheet or the like in corresponding positions opposite the printing plate, means for causing a relative adjustment of said holders for placing different portions of said sensitized plate or layout sheet or the like opposite the printing plate, means for causing a relative movement of said holders toward and from each other to place the printing plate and opposed plate or sheet into and out of contact, pressure means for causing an intimate contact of the sensitized and printing plates, means for illuminating the printing plate, and a holder for a master design arranged to permit the design and the printing plate to be placed in registration with each other.
17. In a photographic printing apparatus, the combination of a holder carrying a printing plate, two holders carrying respectively a sensitized plate and a layout sheet or the like and arranged to interchangeably position said sensitized plate and layout sheet or the like in corresponding positions opposite the printing plate, means for causing a relative adjustment of said holders for placing different portions of said sensitized plate or layout sheet or the like opposite the printing plate, means for causing a relative movement of said holders toward and from each other to place the printing plate and opposed plate or sheet into and out of contact, pressure means for causing an intimate contact of the sensitized and printing plates, means for illuminating the printing plate, and a holder for a master design arranged to permit the design and the printing plate to be placed in registration with each other.

Witness my hand this 30th day of September, 1920.

WILLIAM C. HUEBNER.
